(57) **CLAIM**

The ornamental design for a platform and insert set for a pipe support system, as shown and described.

DESCRIPTION

FIG. 1 is a first perspective view of a platform and insert set for a pipe support system that together may be used as part of a pipe support system, showing my new design;

FIG. 2 is a second perspective view of the platform and insert set for a pipe support system of FIG. 1, with the platform and the insert in exploded-apart relation.

FIG. 3 is a front elevation view of the platform and insert set for a pipe support system of FIG. 1;

FIG. 4 is a rear elevation view thereof, which is a mirror image of FIG. 3;

FIG. 5 is a right side elevation view thereof;

FIG. 6 is a left side elevation view thereof, which is a mirror image of FIG. 5;

FIG. 7 is a top plan view thereof;

FIG. 8 is a bottom view thereof;

FIG. 9 is a perspective view of the platform of FIG. 1, shown without the insert;

FIG. 10 is a front elevation view of the platform of FIG. 1;

FIG. 11 is a rear elevation view of the platform of FIG. 9, which is a mirror image of FIG. 10;

FIG. 12 is a right side elevation view of the platform of FIG. 9;

FIG. 13 is a left side elevation view of the platform of FIG. 9, which is a mirror image of FIG. 12;

FIG. 14 is a top elevation view of the platform of FIG. 9;

FIG. 15 is a bottom view of the platform of FIG. 9;

FIG. 16 is a perspective view of the insert of FIG. 1, shown without the platform;

FIG. 17 is a front elevation view of the insert of FIG. 16;

FIG. 18 is a rear elevation view of the insert of FIG. 16, which is a mirror image of FIG. 17;

FIG. 19 is a right side elevation view of the insert of FIG. 16;

FIG. 20 is a left side elevation view of the insert of FIG. 16, which is a mirror image of FIG. 19;

(Continued)

FIG. 21 is a top plan view of the insert of FIG. 16; and, FIG. 22 is a bottom view of the insert of FIG. 16. The broken lines in the drawings depict portions of the platform that form no part of the claimed designs.
